UNITED STATES PATENT OFFICE.

BRODERICK HASKELL, OF FRANKLIN, PENNSYLVANIA.

RAILROAD TIE.

Application filed June 16, 1927. Serial No. 199,183.

This invention relates to railroad ties, and particularly to ties formed of wood and metal parts combined.

An object of the invention is to make a tie having the strength of a metal structure with the resiliency of wood. Another object is to utilize worn out rails for making ties. Another object is to provide constantly operative means for compensating for shrinkage of wooden parts and for permitting expansion thereof without undue strain on rigid parts. Other objects and advantages will appear in the following specification.

15 It has previously been proposed to construct railway ties from old or discarded rails, with wooden blocks secured thereto for the purpose of receiving the service rails and also to confer, in part at least, some of 20 the advantages inherent in wooden ties. The aim thereof was dual; both to use old rail stock, which had only scrap value, and also to conserve the rapidly diminishing supply of prime quality woods needed for ties.

25 These prior structures, however, so far as I know, have not been satisfactory, and have apparently never attained commercial success, despite the obvious advantages to be secured. One of the chief reasons therefor 30 has been due to the fact that the wooden rail-retaining members swell or shrink as they absorb moisture or as they dry out. In the first case the result is that the wood in swelling may exert sufficient pressure to 35 shear off the threads on clamping bolts, where such means of attachment is used; in the case where the blocks dry out, they may shrink so much that they become loosened, thereby endangering traffic.

40 Accordingly, I have been led to devise a simple means for effectively compensating for these volume changes in the blocks used in ties made up in the manner referred to. By the application of this invention, therefore, it is possible to use discarded rail stock 45 for making such ties, and to gain other advantages, as will be set forth.

The invention is illustrated in the accompanying drawings, of which Fig. 1 represents a plan view of the tie construction; 50 Fig. 2 a side view of the same, showing rails fastened thereto; Fig. 3 a cross sectional view of one form of the tie, taken on line III—III of Fig. 1; and Figs. 4 to 6 represent similar views of another form, Fig. 4

being as before a plan view of the modified tie construction; Fig. 5 a side view of the same; and Fig. 6 a sectional view taken on line VI—VI of Fig. 4.

50 Referring to Figs. 1 to 3, the structural part of the tie is represented by the numeral 1, which is preferably made from discarded rails. In its preferred form, these members are made by first cutting the head from the rail and then rolling the base portion, or otherwise reforming the flange so as to flatten it, resulting in a T-sectional form as illustrated in Fig. 3. These rails are cut to standard tie lengths, two such lengths being used to make each tie. These two 55 lengths are placed side by side, with the web up as shown in Fig. 3, and are spaced apart a suitable distance to receive wooden blocks 2 between them, these blocks being spaced properly to receive the rails 3 when laid, the rails being secured to the blocks in the usual manner, as with spikes 6.

60 In order to prevent grounding of the signal circuits carried by the rails, and also to permit the blocks to absorb the traffic impact, these blocks are preferably cut so that they extend above the wall or web 3, as shown by Fig. 3.

65 In order to securely fasten the blocks to the members 1, and to make the tie structure rigid, the blocks are clamped between these sections, preferably by bolts 4, passed entirely therethrough.

An important feature of this invention 70 consists in the use of a spring device 5, which compensates for any volume changes in the blocks due to swelling or shrinking, and which thereby preserves the tightly-clamped relation of the wood and metal parts of the tie.

75 This spring may be made from any suitable material, such as strong spring steel, and according to the preferred embodiment of the invention is made from plate or strap stock, a suitable length being bent into the 80 bowed form shown in Fig. 1.

85 The formed spring is placed in position between the bolts heads, or nuts, and the wall or web of the rail member 1, in such manner that the outwardly bent ends bear 90 against the bolt heads (or nuts), the middle inwardly bowed portion of this leaf spring then bearing on the web between the bolts. The nuts are then drawn up until the proper 95 clamping action is secured, the construction 100 105 110

being such that the spring is then under stress. The installation is normally made with dry wooden blocks, so that the later movement is expansion and then contraction 5 of the wood.

The action of the spring may be explained as follows. When the wooden blocks expand due to absorption of moisture, these springs take up the resultant thrust, and 10 thereby prevent undue strain on the threads of the bolt. When the wood shrinks, the springs, being initially under stress follow and firmly press against members 1, thereby preventing the blocks from becoming loose 15 therebetween.

Thus it will be readily apparent that the tie structure is both economical, since it makes use of scrap rails instead of large amounts of expensive wood, and also be- 20 cause it will effectively overcome the disadvantages which inhere in prior composite structures of similar nature. It will also be apparent that the blocks may be made from sound portions of old wooden ties as well as 25 from new material. Since the blocks are normally only about one-sixth the length of a tie, there is a saving of two-thirds in new wood. In addition much wood is good enough for such short lengths, though a 30 full length tie might not be cut therefrom. So, too, the intermediate portions of old ties may be good though the ends may be split and useless.

Likewise, it is possible to utilize discarded 35 rails without removing the heads or otherwise reforming them. For example, where means for thus reforming the rails are not at hand, or where this reforming is undesirable for other reasons, it is possible simply to cut 40 the rails to proper tie length. This embodiment of the invention is illustrated by Figs. 4 to 6. In these drawings, an ordinary discarded rail cut to tie length is represented by 10, and the wooden rail-receiving blocks 45 are indicated at 11. Blocks 11 are as before spaced between members 10, and bolts 4^a passed entirely therethrough, the spring 5 being positioned as before and as shown in the figures. The rails as laid are indicated by the numeral 3^a, these being fastened 50 as usual by spikes 6^a.

As in the first embodiment shown, it is desirable to cut the blocks 11 so that they extend above the rail head. In this case it 55 will also be necessary to shape the sides of the blocks to conform to the space between the rail head and flange. This is done by cutting away portions of the sides to leave lateral projections having shoulders 12 and 60 13 adapted to seat beneath and on the rail head and flange, respectively, as shown in Fig. 6.

It will be observed that in both forms, the 65 wooden blocks are seated upon the rail flanges, and the sides are securely held be-

tween the vertical webs. This reinforces the wood blocks on the two sides and bottom, preventing splitting under load.

It is not intended to limit the invention to the leaf-type springs illustrated in the drawings and described in the foregoing specification, since other types may function satisfactorily. However, these leaf springs can be made more cheaply than other types and are also installed more readily than 75 other forms, and for most purposes they are preferred.

In the appended claims the expression "heads of said bolts" is used for clearness and simplicity and is intended to mean both 80 the head end proper and also the nut end, which latter may for the purposes of this invention be considered to act like the head end in regard to the spring action.

I claim:

1. A railway tie comprising a pair of spaced metal sections each having a vertically disposed web and a flange base, rail-supporting blocks of wood arranged between the webs of said sections, clamps for attaching said blocks to said sections, and resilient means acting upon said clamps to prevent undue stress upon them when the blocks expand and to maintain the blocks firmly clamped between the sections when the 95 blocks contract.

2. A railway tie comprising a pair of spaced metal sections each having a vertically disposed web and a flanged base, rail-supporting blocks of wood arranged between the webs of said sections, bolts extending 100 through said blocks and the webs of said sections for clamping the blocks between the sections, and resilient means acting upon said bolts to prevent undue stress upon them when the blocks expand and to maintain the blocks firmly clamped between the sections when the 105 blocks contract.

3. A railway tie comprising a pair of spaced metal sections each having a vertically disposed web and a flanged base, rail-supporting blocks of wood arranged between the webs of said sections, bolts extending through said blocks and the webs of said sections for clamping the blocks between the sections, and springs acting between the heads of said bolts and the webs of said sections to compensate for transverse expansions and contractions of said blocks.

4. A railway tie comprising a pair of spaced metal sections each having a vertically disposed web and a flanged base, rail-supporting blocks of wood arranged between the webs of said sections, bolts extending through said blocks and the webs of said sections for clamping the blocks between the sections, and bowed leaf springs having their ends engaged by the heads of said bolts and their middle portions bearing upon the webs of said sections to compensate for 120 125 130

transverse expansions and contractions of said blocks.

5. A railway tie comprising portions of old rails arranged in a parallel pair, blocks of wood positioned between said rails and adapted to receive track members seating thereon, the blocks being seated upon the rail flanges and clamped between the rail webs, clamping bolts extending through the old rails and blocks, and bar springs posi-

tioned between the bolts and outer sides of the webs of the old rails, said springs engaging the bolts at their ends and engaging the rail webs between the bolts, the springs being inwardly bowed between the bolts, 15 whereby to exert constant inward pressure on the rail webs.

In testimony whereof, I sign my name.

BRODERICK HASKELL.
